UNITED STATES PATENT OFFICE.

JACOB M. STRICKLER, OF RICHMOND, VIRGINIA.

WATER WHEEL.

Application filed June 27, 1923. Serial No. 648,065.

To all whom it may concern:

Be it known that I, JACOB M. STRICKLER, a citizen of the United States, residing at Richmond, in the county of Henrico and 5 State of Virginia, have invented certain new and useful Improvements in Water Wheels, of which the following is a specification, reference being had to the accompanying drawings.

10 This invention relates to water wheels, and particularly to turbine water wheels, which take the water through an upper gate, the flow of water being downward through the wheel and being regulated by a suitable 15 valve or register disposed at the upper end of the gate.

The general object of this present invention is to improve the construction of wheels of this character by providing a water 20 wheel having blades or buckets of such form that the flow of the water will impact against the wheel at two points and the water will then be discharged against a series of abutments formed on the inside of 25 the casing of the wheel whereby to secure a reaction and a propulsive effect upon the water wheel which would otherwise be impossible to secure.

A further object is to provide a wheel of 30 this character so constructed that the centrifugal action of the wheel discharges the water outward against abutments to secure an impact between the wheel and the casing, thus securing two elements of force, 35 the blades or buckets being furthermore so constructed as to cause a whirl of the water above the wheel, thus adding velocity to the current of the water and speed to the wheel.

Other objects will appear in the course of 40 the following description.

My invention is illustrated in the accompanying drawings, wherein:

Figure 1 is a vertical diametrical section through my improved water wheel;

45 Figure 2 is a section on the line 2-2 of Figure 1;

Figure 3 is a top plan view of the water wheel, the shaft 33 being in section;

Figure 4 is a section on the line 4-4 of 50 Figure 3;

Figure 5 is a perspective view of one of the blades of the wheel;

Figure 6 is a perspective view of another form of blade.

55 Referring to these drawings, 10 design-

nates the lower section of the wheel casing, this section being approximately cylindrical in form and having the outwardly projecting flange 11. Mounted upon this flange 11 is a ring 12 which projects inward beyond this flange and has its inner edge rounded or beveled downward and centrally, as at 13. Disposed upon this ring 12 is the upper section 14 of the wheel casing, this upper section being formed with a flange 15 at its lower end resting upon the ring 12. The flange 11 and the ring 12 may be bolted or otherwise connected to each other. The lower end of the section 10 is formed with a radially disposed spider 16. This spider carries a step bearing 17. The spider may be integral with the lower section 10 of the casing or may be attached thereto in any suitable manner.

The upper section is formed as illustrated in Figure 1, with a web 18 extending over the top of the upper section and cut out to provide a plurality of openings 19. These openings are tangential with relation to a circle concentric to the axis of the casing and the outer ends of the openings are wider than the inner ends of the openings. These openings extend from the hub 20 of this web 18 to the wall of the section 14. The portions of the web 18 between the openings 19, as illustrated in Figure 4, have a vertical face 21 and a downwardly inclined or rounded face 22, and the web 18 has a central hub 20, as before stated, having a shaft opening therethrough.

Disposed upon this web 18 and oscillatably mounted thereon around the hub 20 is a register gate, designated generally 23, having an annular hub 24 and a series of tangential openings 25, each opening having the same area and form as the openings 19 and being adapted to register therewith or to be shifted out of register therewith. One wall 26 of each opening 25 is straight, that is vertical, while the opposite wall is inclined or rounded downward and forward, as at 27. These faces 27 act to direct the water downward and forward as it passes into the upper section of the casing and the water directed downward and forward by the faces 27 is again directed in this manner by the rounded faces 22 of the web 18 immediately beneath.

The register gate 23 has a range of oscillation such that when it is fully turned in

one direction the openings 19 will be entirely closed by the gate and when it is fully turned in the opposite directions the openings 25 will register fully with the openings

5 19. Obviously the gate might be turned to only bring the openings 25 and 19 into partial register, thus reducing the amount of water flowing through the gate into the casing beneath.

10 In order to limit the rotation of the gate 23, I provide on the gate the downwardly projecting studs or lugs 28 which operate in recesses 29 formed in the outer face of the wall of section 14, these recesses having a

15 length exactly equal to the width of the openings 19 at their outer ends. There may be a number of these recesses and a number of the lugs 28 engaging in the recesses or the gate may be turned in any suitable manner

20 but I do not wish to be limited to this. I have illustrated, however, the gate as having a pair of upwardly projecting pins 30 with which a wrench may be engaged to operate the gate. This is purely illustrative 25 and it will be understood that gearing might be provided for adjusting the gate.

The lower section of the turbine, as before stated, is provided with the spider 16 and the step bearing 17. The inner face of this 30 section is formed with a plurality of vertically extending shoulders or abutments 31. In other words, the inner face of the section is formed like an internal ratchet wheel so that the apex of each shoulder or abutment 31 and inclined face 32 extends to the base on the next adjacent shoulder or abutment 31. These shoulders or abutments 31 face away from the direction in which the rotor 35 or wheel is to rotate.

40 Disposed through the center of the casing formed by the sections 10 and 14 is a shaft 33. This shaft is stepped within the bearing 17 and is supported at its upper end in the bearing formed in the center of the annular hub 20. I do not wish to be limited to any particular form of bearing for this 45 shaft. Mounted upon the shaft is a blade or bucket carrier 34 which may be supported in any suitable manner thereon and which is formed with the downwardly and outwardly extending flange 35. At the junction of the carrier 34 with its flange there are formed the sockets 36 having a dove-tail form. Attached to this runner, carrier or 55 equivalent member 34 are a plurality of blades 37, one of which is illustrated in Figure 5. I do not wish to be limited to the exact form of blade shown, but I have illustrated a blade having a somewhat rectangular form, this blade being twisted in its length and provided upon its inside edge with the outwardly projecting lug 38 which is adapted to be received in the dovetailed slot 36 and locked therein. The blade, as 60 before stated, is twisted and below the lug

the blade is widened, as at 39, and is formed with an outwardly projecting flange 40. The blade is supported at a downward and outward angle.

The water in discharging through the 70 apertures 19 and 25 strikes the upper portion of the blade, then strikes the flange 40 and is then discharged against the abutments or shoulders 31. If the flanges 40 were left off the blades and there were no 75 abutments 31, the downward movement of the water would cause a rotation of the wheel formed by the runner and blades, but the flange 40 secures from the water an additional impelling power and this is 80 further increased by the reaction of the water dashing off of the flange 40 and the lower portion of the blade and striking the abutments. I have found in actual practice 85 that this secures the full force of the water on the blades and that the water after it leaves the lower end of the casing 10 is "dead," all of its force having been expended against the wheel.

I have illustrated in Figure 6 a slightly 90 different form of blade, which I have designated 37^a, but which is designed to attain the same end. The difference between the blade 37^a and the blade 37 simply lies in the manner in which the lower edge of the 95 blade is curved, as at 37^b, and the fact that the flange 40^a does not extend at right angles to the blade but merges into the blade.

It will be understood that the upper end 100 of the shaft 33 may have any suitable coupling or other means whereby it may be connected to a shaft to be driven by the shaft 33, but I do not wish to be limited to any particular means for this end. I have illustrated a conventional construction for this 105 purpose. I have also illustrated a ring 41 engaged with the upper ends of the outwardly projecting portions of the blades for the purpose of holding these blades, this 110 ring acting to strengthen the blades.

In the operation of my mechanism, the water passes vertically downward through the gate openings and then the column of water strikes the upper ends of the buckets. These upper ends do not extend radially outward but at a slight inclination to the radial, the upper end of the blade being slightly more forward than the inner end of the blade. The blade is inclined downward and rearward to some extent, but as the blade extends downward it always twists rearward and at its lower end is broadened. Above this lower end there is disposed the inwardly extending member 13 with its beveled 115 face. This contracts the area of the passage-way through which the water is descending and causes the water to be forced inward at a high speed and with an increase of pressure against the lower end of the upper portion of the blade so that the blade not only 120

receives the downward impact of the water but it also receives the force exerted by the inward movement of the water in getting past this contracted opening 13. Below this opening the water moves downward and outward radially by reason of the curved twist at the lower portion of the blade and is discharged outward, as best shown in Figure 2, and the water is discharged against the flange 40, causing the forward movement of the wheel, and this flange 40 causes the water to be discharged outward and rearward against the abutments 31. I have found in actual practice that much greater power is secured from this wheel than without the specific construction illustrated, and this is particularly due, in my opinion, to the contracted opening defined by the ring or flange 13 and the use of the abutments 31 and to the particular form of the blades which are first acted upon by the downward movement of the water and then by the outward and downward movement of the water and the impact of the water against the inner face of the corrugated or toothed casing. The water as it enters the casing moves in the direction of the wheel, enters the blades gently, and takes a gliding action, strikes the outer casing with force, and rebounds back against the incoming water, forming a shoving force against the casing and runner. The force is then spent and the water has lost all its force when it leaves the casing.

While I have illustrated a certain definite construction which I believe to be particularly effective, I do not wish to be limited thereto as it is obvious that many changes might be made without departing from the spirit of the invention.

I claim:—

1. In a water wheel, an outer casing, the upper and lower ends of the casing being formed with inlet and outlet openings respectively, a shaft extending into the casing, blades mounted upon the shaft, each blade being so formed as to receive the impact of the descending water and direct the water outward against the wall of the casing, the wall of the casing being formed with a series of vertical shoulders against which the water from the blades is discharged and the apex of one shoulder being connected to the base of the next shoulder by an inclined face, the shoulders being opposed to the direction in which the wheel is designed to move, the casing being formed with an inwardly projecting annular flange above the lower portion of the blades, the upper face of the flange being inclined downward and inward.

2. A water wheel comprising a casing, the upper end of the casing having a series of sector-shaped openings extending outward from the center of the casing, the rear wall

of the opening being vertical and the forward wall being downwardly and forwardly inclined, a register gate mounted upon the casing over said openings and having openings of the same form and area as the openings in the casing, the forward wall of each opening in the register gate being downwardly and forwardly inclined and the rear wall being straight, means for oscillating said gate to control the effective area of said openings in the casings, a shaft passing downward through the casing and supported in bearings therein, a runner mounted upon the lower end of the shaft, and blades carried by the runner, said blades being twisted and formed each at its lower end and outside edge with a rearwardly projecting flange, the inside face of the casing having a series of shoulders facing in the direction of rotation of the shaft and against which the water is caused to be directed by the flanges on the blades.

3. A water wheel comprising a casing, the upper end of the casing having a series of sector-shaped openings extending outward from the center of the casing, the rear wall of the opening being vertical and the forward wall being downwardly and forwardly inclined, a register gate mounted upon the casing over said openings and having openings of the same form and area as the openings in the casing, the forward wall of each opening in the register gate being downwardly and forwardly inclined and the rear wall being straight, means for oscillating said gate to control the effective area of said openings in the casings, a shaft passing downward through the casing and supported in bearings therein, a runner mounted upon the lower end of the shaft, and blades carried by the runner, said blades being twisted and formed each at its lower end and outside edge with a rearwardly projecting flange, the inside face of the casing having a series of shoulders facing in the direction of rotation of the shaft and against which the water is caused to be directed by the flanges on the blades, the casing having an inwardly projecting annular flange disposed above the lower portions of the blades and below the openings in the upper ends of the casing, this flange being downwardly and centrally beveled upon its upper face.

4. A water wheel comprising a casing, the middle portion of which is contracted, the casing being open at its top and bottom, a shaft extending into the casing, and blades mounted upon the shaft, each blade being approximately radial to the shaft, the upper portions of the blades being narrower than the lower portions and the lower portions projecting outward beneath the contracted portion of the casing, the blades being twisted rearward from their upper portions to their lower portions, and the outer mar-

gin of the lower portion of the blade being formed with a rearwardly extending flange.

5. In a water wheel, an outer casing, the upper and lower ends of the casing being formed with inlet and outlet openings respectively, the middle of the casing having a contracted portion, a shaft extending into the casing, and blades mounted upon the shaft, each blade being so formed as to receive the impact of the descending water at a slight angle to the direction of the water and then to direct the water outward and

downward against the lower portion of the wall of the casing and the wall of the casing 15 being formed with a series of vertical shoulders against which the water from the blades is discharged, all of the blades having relatively narrow upper portions extending through the contracted portion of the casing 20 and relatively wide lower portions extending outward nearly to the wall of the casing.

In testimony whereof I hereunto affix my signature.

JACOB M. STRICKLER.
